ROUND PANEL LAMP

Gene I. Thomasson, Wickliffe, Ohio, assignor to General
Electric Company, a corporation of New York

Continuation of design applications Ser. No. 63,417,
Jan. 3, 1961, and Ser. No. 66,834, Sept. 25, 1961. This
application Jan. 2, 1963, Ser. No. 73,178

Term of patent 14 years

(Cl. D48—23)

FIG. 5

FIG. 6

FIGS. 1 to 4 illustrate a round panel lamp forming one embodiment of my new design wherein:

FIG. 1 is a bottom plan view;

FIG. 2 is a reduced top plan view;

FIG. 3 is a fragmentary sectional view looking in the direction of the arrows 3-3 in FIG. 1, and

FIG. 4 is a side elevation view.

FIGS. 5 and 6 illustrate a round panel lamp forming another embodiment of my new design wherein:

FIG. 5 is a bottom perspective view, and

FIG. 6 is a bottom plan view.

The dominant features of my new design are shown in solid lines with shading in the drawings.

This application is a continuation of my copending ap-

plications D. 63,417, filed January 3, 1961, and D. 66,834, filed September 25, 1961, both now abandoned.

I claim:

The ornamental design for a round panel lamp, as shown and described.
